FOUR-WAY PALLET

Edward L. Bartee, Van Nuys, Calif., assignor of one-half to Bernard B. Greene, Los Angeles, Calif.

Filed June 26, 1969, Ser. No. 17,898

Term of patent 7 years

Int. Cl. D12—99

U.S. Cl. D14—3

FIG. 1 is a front perspective view of a four-way pallet showing my new design;

FIG. 2 is a top plan view;

FIG. 3 is a bottom plan view;

FIG. 4 is a side view;

FIG. 5 is an end view; and

FIG. 6 is a cross-sectional view of the pallet of FIG. 1 taken along the plane VI—VI.

I claim:

The ornamental design for a four-way pallet, as shown.
